INVENTOR.
Joseph B. Fischer,
BY *Robert Burns,*

ATTORNEY.

UNITED STATES PATENT OFFICE

JOSEPH B. FISCHER, OF CHICAGO, ILLINOIS

FERMENTATION BUNG

Application filed December 9, 1931. Serial No. 579,917.

This invention relates to that type of valved fermentation bungs by means of which gases formed during a fermentation process in a closed container, are permitted to freely escape while a passage of outer atmosphere to the interior of such container is effectively prevented. And this improvement has for its object:

To provide a structural formation and combination of parts of the valve member of a fermentation bung, of a simple and durable nature, by means of which a passage of atmospheric air into the closed container in which the fermentation operation takes place, is effectively prevented while permitting a free and ready escape of the gases evolved during the progress of such operation, all as will hereinafter more fully appear.

In the accompanying drawing:

20 Fig. 1 is a vertical section, elevation partly on line 1—1. Fig. 2, of a fermentative bung embodying this invention.

Fig. 2 is a detail horizontal section on line 2—2, Fig. 1. Like reference numerals indicate like parts in both views.

In this invention the main and fixed portion of the valve housing comprises a cylindrical shell 1, closed at its upper end by a detachable flanged cap or head 2 having a central inlet-outlet orifice 3, adapted to permit of a ready introduction of a filling of water into the interior of the valve housing; at its lower end the shell is permanently closed by a flanged head 4, as shown.

35 In the present construction the fixed head 4 is formed with a central orifice through which passes a vertical tube 5 that is fixedly secured to said head by attaching washers 6, on the upper and lower faces of the head, as shown in Fig. 1.

The upper portion of the vertical tube 5 extends up in the interior of the valve housing to near the upper end of the same, with the open upper end of said tube forming the fixed annular seat or member of the present valve structure. The lower portion of said vertical tube depends below the valve housing and is attached to a closure head or bung 7, adapted to fit the bung hole of a barrel or like vessel used in the process of fermenta-

tion, an example of it is shown and described in my prior Patent No. 1,477,552, dated December 18, 1923.

Loosely encircling the portion of the vertical tube within the valve housing, is a tubular member or sleeve 8, the upper end of which is provided with a closure head 9 of cork or like yielding material, to constitute the movable valve head or member of the valve structure, and in connection with the annular seat formed by the upper end of the vertitube 5 is adapted to control the passage to and from said tube.

At its side the shell 1 is formed with an orifice 10 at a predetermined distance below the top of said shell and adapted to permit an outflow of an excess of water that may be introduced into the interior of the valve housing.

In practical use, an outward movement of the gases evolved in the process of fermentation, through the vertical tube 5 acts to lift the movable valve head 9 away from its closure contact with the upper end of said tube, thus permitting a downward flow of the gas through the annular channel between the tube 5 and its encircling sleeve 8, and from under the lower end of the sleeve 8, to pass up through the body of water contained in the main housing of the valve.

With the present construction, any tendency, due to a reduced pressure in the interior of the closed fermentation vessel, to draw air from the outer atmosphere to meet such reduction in pressure, is not only prevented by the filling of water in the valve housing, but is additionally insured by a closed condition of the movable valve head 9, aforesaid.

Having thus fully described my invention, what I claim as new, is:

1. A valve structure for fermentation bungs, comprising a housing formed by a cylindrical shell, a removable closure head at top of said shell and a fixed closure head at the bottom of the shell, a vertical tubular member fixedly secured in the aforesaid lower head with its upper end constituting a stationary annular valve seat, with its lower portion depending for attachment to a bung or closure head, and a tubular sleeve en-

circling said vertical member and carrying in its upper end an elastic valve head adapted for closure contact with the upper end of said vertical member.

5 2. A valve structure for fermentation bungs, as specified in claim 1, and wherein the vertical tubular member is secured in place in the lower head of the valve housing by attaching disks on the respective faces of

10 said lower head.

3. A valve structure for fermentation bungs, as specified in claim 1, and wherein the removable head of the valve housing is formed with a central inlet-outlet passage.

15 In testimony whereof I hereunto affix my signature.

JOSEPH B. FISCHER.
